DESIGN FOR A GEAR FINISHING MACHINE

Edward W. Miller, Springfield, Vt., assignor to
The Fellows Gear Shaper Company, Springfield,
Vt., a corporation of Vermont

Application April 13, 1944, Serial No. 113,241

Term of patent 14 years

(Cl. D54—14)

To all whom it may concern:

Be it known that I, Edward W. Miller, a citizen of the United States, residing at Springfield, in the county of Windsor and State of Vermont, have invented a new, original, and ornamental Design for a Gear Finishing Machine, of which the following is a specification, reference being had to the accompanying drawings, forming a part thereof.

In the drawings,

Figure 1 is a top plan view of a gear finishing machine showing my new design;

Figure 2 is a front elevational view thereof;
Figure 3 is a rear elevational view thereof;

Figure 4 is a side elevational view as seen from the left of Figure 2; and

Figure 5 is a side elevational view as seen from the right of Figure 2.

The dominant features of the design reside in the portions shown in full lines.

I claim:

The ornamental design for a gear finishing machine, as shown and described

EDWARD W. MILLER.
